US00D844514S

(12) **United States Design Patent** (10) **Patent No.:** **US D844,514 S**
(45) **Date of Patent:** **** Apr. 2, 2019**

(54) **MULTI-FUNCTIONAL JOYSTICK FOR AN AGRICULTURAL VEHICLE**

(71) Applicant: **Deere & Company**, Moline, IL (US)

(72) Inventors: **Christoph Wagner**, Reilingen (DE); **Sebastian Himpel**, Mannheim (DE); **Thorsten Hagner**, Ilvesheim (DE); **Nicolas Staack**, Hedesheim (DE); **Jonathan E. Drum**, Raleigh, NC (US)

(73) Assignee: **DEERE & COMPANY**, Moline, IL (US)

(**) Term: **15 Years**

(21) Appl. No.: **29/634,510**

(22) Filed: **Jan. 23, 2018**

(30) **Foreign Application Priority Data**

Jul. 26, 2017 (EM) 004121028

(57) **CLAIM**

The ornamental design for a multi-functional joystick for an agricultural vehicle, as shown and described.

DESCRIPTION

FIG. 1 is a perspective view of a multi-functional joystick for an agricultural vehicle embodying our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken line representations in the figures show unclaimed environment or boundaries, and thus form no part of the claimed design.

1 Claim, 7 Drawing Sheets
